CHESTER F. MEYER, OF CLEVELAND, OHIO, ASSIGNOR TO THE NATIONAL MALLEABLE CASTINGS COMPANY, OF CLEVELAND, OHIO, A CORPORATION OF OHIO.

RADIAL-DRAFT GEAR.

1,209,187.

Specification of Letters Patent. Patented Dec. 19, 1916.

Application filed May 18, 1915. Serial No. 23,813.

To all whom it may concern:

Be it known that I, CHESTER F. MEYER, a citizen of the United States, residing at Cleveland, Cuyahoga county, Ohio, have invented new and useful Improvements in Radial-Draft Gears, of which the following is a specification, reference being had to the accompanying drawings, in which—

Figure 1 is an elevation partly in section 10 of a radial draft gear embodying my invention; Fig. 2 is a plan thereof, partly in section; Fig. 3 is a section on lines 3—3 of Fig. 1; and Fig. 4 is a section on lines 4—4 of Fig. 1.

15 My invention relates to radial draft gears and consists in an arrangement in which the draft member is comprised of a pair of telescoping casings, one of which is adapted to receive a friction rigging preferably of the 20 twin or parallel spring type.

My invention also relates to the construction and coöperation of the parts which I shall hereinafter describe and claim.

Referring to the drawings A indicates the 25 coupler; B the outer casing of the draft member; C the inner casing of the draft member, and D the shock absorbing mechanism, which I have shown in the form of a friction mechanism of the twin or parallel 30 spring type.

The outer casing B has a pocket 2 for the coupler shank, at its forward end, separated from an intermediate chamber 3 for reception of the inner casing, C, by a wall or partition 4, and two rearwardly extending slotted arms 5. The partition is operative only in buffing to provide a bearing for the forward end of the inner casing after the cushioning mechanism goes solid. The 40 slotted arms 5 of the casing B are designed for reception of the ends of a key or follower 6, which seats in slots 7 in the arms 5 of the outer casing B, and through which, under draft, the stresses are transmitted 45 from the outer casing to the shock absorbing mechanism D against which the forward side of the key 6 bears.

The inner casing C consists of the arms 8, 50 arranged one above another, and connected at their forward ends by vertical side flanges 9, and by a forward wall 10 having an aperture 11 therein to permit the coupler butt to bear directly against the shock absorbing mechanism during buffing. At

the rear end of the casing the arms 8 are 55 joined by a cross piece 12, having flanges 13, extending rearwardly therefrom, arranged to interfit with forwardly extending bosses 14 on the pivot casting 15, and thereby put the pivot pin 16 in quadruple shear. Intermediate of the ends of the casing C are 60 preferably provided inwardly extending projections 17, against which the shoulders 18 on the friction case will strike when the friction mechanism goes solid. 65

In assembling the gear the shock absorbing mechanism D which I have shown in the form of a friction case, intended to receive a twin spring friction mechanism, is placed in the casing C from the side and then is 70 skidded toward the forward wall 10 of the casing C so that it will be held in place laterally by the flanges 9. The rear of the open end of the friction case is enlarged by the bosses 19, which bear upon the outer casing 75 B and keep the rear end of the friction case in lateral alinement by their bearing against the inner faces of the arms 5 of the outer casing B. The outer casing B is next slid over the inner casing C, and the key or follower 6 is inserted through the slots 7 and brought into bearing between the frictional parts 20 of the mechanism D and the cross piece 12 of the inner casing C. The coupler 80 A may then be inserted into the pocket 2, its butt passing through the opening in the inner casing, and bearing directly upon the forward face of friction case D. The coupler is locked in place by the keys 21, which seat in slots 22 of the case B. Under draft 85 the coupler pulls the outer case B forwardly, which carries with it the key 6, which bears against the rear end 20 of the shock absorbing mechanism D. The inner casing C holds the shock absorbing case 90 from forward movement, and as the key 6 is pulled forwardly by the outer casing it 95 will compress the friction mechanism.

In buffing as the outer casing B is secured to the coupler by the locking keys 21, it will 100 move rearwardly with the coupler, and the coupler butt, which is in contact with the friction case, forces it rearwardly within the inner casing. The key 6 under buffing bears against the cross piece 12, which in turn is in contact with the pivot casting 105 and is, therefore, held stationary. When the shock absorbing mechanism under heavy

buff, has reached the limit of its travel, and has gone solid, the shoulders 18 of the friction case strike against the projections 17 on the inner case C and relieve the friction 5 elements from further stress. The partition 4 in the outer casing will also simultaneously strike the forward wall 10 of the inner casing, so that a portion of the excess shock is transmitted directly to the pivot casting 10 by the casings and the remainder is carried by the shock absorbing mechanism through the key 6 to the pivot casting 15.

The terms and expressions which I have employed are used as terms of description 15 and not of limitation, and I have no intention in the use of such terms and expressions of excluding any mechanical equivalent for the features shown and described, but recognize that various structural modifications 20 are possible within the scope of the invention claimed.

What I claim is:

1. In a radial draft gear, an outer casing having a coupler secured thereto and having 25 a plurality of rearwardly extending arms, an inner casing having a plurality of rearwardly extending arms connected with each other by a cross piece near their rear ends and having a point of pivotal attachment to 30 a car, a shock absorbing mechanism seated in the inner case, and a follower having a bearing on arms of the outer casing, the

cross piece and on the shock absorbing mechanism.

2. In a radial draft gear, a pair of telescoping casings, a bracket secured to the car having a plurality of forwardly-extending apertured bosses, one of said casings having a plurality of rearwardly-extending apertured projections, a pivot pin seated in the 40 apertures in said bosses and projections, in combination with a container for shock-absorbing mechanism seated in one of said casings, and a follower having a bearing between said last-mentioned casing and the 45 shock-absorbing mechanism, said follower also being actuated during draft to compress the frictional mechanism against the first-mentioned casing.

3. In a radial draft gear, an outer casing 50 attached to a coupler, an inner casing pivotally attached to the car, a container for shock absorbing mechanism positioned within the inner casing, coöperating shoulders upon the outer casing and the inner casing, coöperating projections upon said container and inner casing, said sets of shoulders and projections being brought into engagement at the end of the compressive movement of the shock absorbing mechanism under buffing 55 movement of the gear and being adapted to relieve said shock absorbing mechanism from further stress.

CHESTER F. MEYER.
